UNITED STATES PATENT OFFICE

2,043,892

VALVE FOR LIQUID FUEL BURNERS

Adolph A. Halter, Cleveland, Ohio

Application November 14, 1935, Serial No. 49,833

1 Claim. (Cl. 137—104)

This invention relates to a liquid fuel burner, particularly designed to burn gasoline or coal oil.

It is aimed to provide a novel construction 5 minimizing the danger of explosion and which operates automatically to cut off the supply of the fuel in the event of flooding or undue feed thereof.

A further object is to provide a construction 10 wherein a float means operates automatically to attain the end mentioned.

The more specific objects and advantages will become apparent from a consideration of the description following taken in connection with accompanying drawing illustrating an operative embodiment.

In said drawing:—

Figure 1 is a view in elevation illustrating the improved burner; and

Figure 2 is a vertical sectional view, on an enlarged scale, taken through the improved burner.

Referring specifically to the drawing, a burner as an entirety is designated 10, preferably being annular and having inner and outer, upwardly flaring walls 11 and 12, respectively, joined by a base wall 13. Such walls provide a chamber 14 which contains a conventional annular wick 15, a conventional chimney therefor being shown at 16.

Surrounded by the burner and suitably supported within the same is a fuel control chamber or tank 17 which is supplied with fuel, such as gasoline or coal oil from a tank 18, arranged at such a level that the liquid fuel will flow by gravity therefrom through pipes 19 into the interior of the tank or chamber 17, a fuel pipe joint being provided at 20 where such pipe 19 passes into the chamber 17.

Coacting with the outlet end of the pipe 19 40 is a needle valve 21 which is slidably mounted in a tube 22 forming part of a bracket 23 fastened within the chamber 17. A bracket 24 suitably supported within said chamber 23 has an

L-shaped lever 25 pivoted thereto as at 26 and at one end of which it is connected by a pin and elongated slot 27, pivotally and slidably joining the valve 21. The other end of said lever 25 carries a float 28 which is controlled by the fuel within the chamber 17 and which is normally adapted to be maintained at substantially the level suggested by dotted lines in Figure 2. The fuel from chamber 17 passes through a pipe 29 to the base of the chamber 14, so that it may be 10 retained by the wick 15 through capillary attraction.

The parts are so constructed and arranged that the fuel at the normal level in the chamber 17 and the base 14, the needle valve 21 will 15 be open so as to afford a continuous supply. However, in the event of an undue rise in fuel, extinction of the flame or the like, the float 28 will be raised by the fuel level, thus rocking lever 25 and pushing the valve 21 against its 20 seat at the end of pipe 19 and thus cutting off the supply of fuel.

Various changes may be resorted to provided they fall within the spirit and scope of the invention.

25 I claim as my invention:—

A device of the class described having a chamber, a supply pipe rising from the bottom wall of the chamber and terminating in a horizontal outlet portion constituting a valve seat at its 30 free end, a bracket depending from the top wall of the chamber having a sleeve aligned with and spaced from the outlet of said portion, a valve slidably disposed in said sleeve extending into said space and adapted to seat directly on the 35 said free end of said portion, a bracket within the chamber, a float, said float having an upwardly extending arm pivoted to the second mentioned bracket below said valve, and being also pivotally connected to said valve on the 40 opposite side of the sleeve to said portion.

ADOLPH A. HALTER.
